UNITED STATES PATENT OFFICE.

BENJAMIN F. HUTCHISON, OF LOS ANGELES, CALIFORNIA.

METHOD OF AND MEANS FOR PRODUCING MULTICOLOR PRINTING PLATES.

Application filed November 30, 1925. Serial No. 72,161.

This invention relates to the novel creation of a negative adapted for the purpose of producing by the photo-engraving or related processes a printing plate suitable to 5 be one of a set of plates for printing multi-colored pictures.

An object of my invention is to produce a novel composite and mechanical negative from which may be produced one of a set of 10 plates for printing multi-colored pictures.

An advantage and object of my novel method is to enable the photo-engraver to produce with less labor, and less skilled labor, a printing plate to be used as one of 15 a set for multi-colored printing.

Another object and advantage of my novel method is that the photo-engraver may economically produce a printing plate for use as one of the set of plates for multi-colored 20 printing, and for use in conjunction with an ordinary printing plate which the owner has already purchased and probably used in the production of one-color prints.

Other objects, advantages and features 25 of invention may appear from the accompanying drawing, the subjoined detail description and the appended claims.

The accompanying drawing illustrates 30 more or less diagrammatically an application of my novel method and invention in producing a negative from which a printing plate may be produced.

Figure 1 illustrates a plan view of the 35 prepared negative base. Portions are broken away to contract the view.

Fig. 2 shows the negative base having an impression of the key plate imprinted thereon and a portion of which imprint is dusted with rotten stone.

Fig. 3 is a fragmental view of the sheet 40 shown in Fig. 2 with the application of powdered graphite to the rotten stone dusted imprint of the key plate.

Fig. 4 shows the sheet illustrated in Fig. 45 3 having a portion thereof painted over with the water soluble opaque paint.

Fig. 5 shows a fragment of the sheet illustrated in Fig. 4 with the key plate mold removed.

Fig. 6 is a view analogous to Fig. 4 illustrating varied combinations of blocking out

portions of the negative base to obtain various combinations of design.

Fig. 7 is a view analogous to Fig. 5 using the design shown in Fig. 6. 55

Fig. 8 is a greatly enlarged section taken on line x^8 , Fig. 6.

Fig. 9 is a plan view of the negative base illustrated in either Figs. 5 or 6 with the opaque paint removed and in condition to 60 again receive an imprint of a key plate.

In carrying out my novel method I first produce a negative base 1 in the following manner:

The negative base 1 is prepared by imprinting, or lithographing, or drawing, or imposing by any other suitable means upon a transparent sheet 2, a negative of any desired design 3, such as a half tone dot, etc. For this purpose a black and opaque printing ink may be used and the negative of the design is printed thereon as in letter press printing, and while the ink upon such transparent sheet 2 is still wet, I prefer to dust it with red lead or any size powder of a different color from the ink used in the printing in order that the workmen may readily distinguish in future operations the different sides of the negative base by its color. When the printed surface is fully dried, the 80 surplus size powder is removed by dusting the sheet with a cloth or brush, or by washing in water, and the sheet is then thinly covered on the side upon which the design has been imprinted with a transparent protective coating or covering 4. This thin transparent protective covering protects the design negative and transparent sheet in subsequent operations as will be more fully hereinafter explained. 85

For the transparent sheet 2, I prefer to use a transparent cellulose, such as celluloid or cellophane having a thickness of from 3 to 10 one thousandths of an inch. If the material selected is celluloid, the negative design imprinted thereon may be thinly sprayed by an air brush, with clear varnish diluted with pure turpentine, or the varnish may be flowed over the surface and the surplus drained off to thus form the protective 95 covering 4. If the material selected is cellophane the sheet and the negative design 100

printed thereon may be protected with a protective covering of liquid nitro-cellulose, either sprayed or flowed thereover as with the varnish.

5 I have described the materials used in the production of the negative base by way of illustration only, and do not wish to be limited thereby; it being understood that any transparent sheet having an opaque negative de-
10 sign imprinted thereon and then protected by a thin transparent coating of a character that will protect the base and negative design from the action of gasoline, or similar solvent and from the action of water, 15 and which produces a smooth hard surface from which an embossed and friable key plate mold may be easily removed will answer.

In addition to the negative base above de-
20 scribed the workman is provided with a water soluble opaque paint, brushes, pans, chamois and paper stumps, clean cotton, and gasoline or similar solvent.

Before proceeding to make, by my method, 25 a set of printing plates to be used for multi-color printing, there will first be made by any of the customary methods a printing plate (not shown) embodying the lines of the drawing or picture to be reproduced in 30 the multi-colored print. This printing plate may be, and in my practice usually is, subsequently used as one of the completed set of plates, or after having served its purpose in carrying out the steps in my process it 35 may be discarded and another plate substituted for it in the finished set. This plate may also contain other lines in addition to the lines of the drawing or picture guide lines which are guide lines for use in the 40 production of the negatives for the other plates of the set, or this plate may be one which has been previously used for single color prints, and is now desired to be used as one of a set for multi-color printing; the 45 other members of the set being produced from negatives made by my process. This plate I designate as the key plate, and the plates of the set made from negatives produced by my process I designate as supple-
50 mentary plates.

The workman will first imprint an impression 5 of the key plate upon the negative base, preferably upon the side upon which the protective coating is applied and which 55 side is easily distinguishable by the red lead dusting of the negative design. I prefer to make this impression upon the protective coating of the negative base because when the negative base is used as a negative the im-
60 pression will be in contact with the sensitized metal because the thickness of the coating 4 is much thinner than the sheet 2.

This impression of the key plate is made in ordinary printing ink, and while the 65 impression is still wet, the printed image is

dusted with rotten stone or similar dry powder, the object being to build up, emboss or raise the lines of the impression, and to render the embossed image when dry of a soft and friable character. This is shown at 70

6, Fig. 2. The workman may then dust the print with powdered graphite for the purpose of rendering the embossed and friable image water proof, at α as shown in Fig. 3. The whole surface of the negative base may 75 then be coated with a solution consisting of the white or albumen of one egg mixed with about one pint of water, using a soft paper to blot up the surplus albumen from the surface of the negative base, the object 80 being to obtain a very thin coating of albumen, so that the water soluble opaque paint to be later applied to portions of the negative base as later described will not crawl, but lay evenly and easily. This embossed 85 opaque, friable and waterproof image upon the negative base, I designate as the key plate mold.

All of that portion of the negative base 90 not covered by the key plate mold, which is not to be transparent in the completed negative, is now painted over as shown in Fig. 4 with the opaque water soluble paint 7, the lines of the drawing in the key plate mold 95 being raised or embossed on the surface of the negative base serve both as a guide, and as a check, dam or control of the flowing opaque paint, thereby increasing the speed by which the work may be done, decreasing 100 the amount of care and skill required of the workmen, and insuring precision of register in the final multi-colored print.

When the opaque paint is dry, all or any portion of the key plate mold may be removed. As it is friable and embossed, this 105 may be done with a paper stump or soft piece of wood or similar instrument, and being soluble in gasoline or similar solvent may be washed away by such solvent.

The opaque paint may be painted entirely 110 over the key plate mold, and the workmen can still easily and with precision remove all or any portion of the key plate mold lines. The embossing or the raising of the lines 115 of the key plate mold further enable the workmen to distinguish the drawing or lines of the picture embodied in the key plate mold, even when such lines may be painted over with the water soluble opaque paint, 120 which lays thin and flat upon the negative base, thereby leaving the key plate mold line in relief; whenever this is done, i. e., the key plate mold lines painted over with opaque, and the key plate mold lines removed, I designate the result "as a key plate mold negative" shown at A in Fig. 7, and whenever 125 and wherever, the key plate mold is permitted to remain as shown by the design at B in Fig. 4, I designate the result as a "key plate mold positive." It will be obvious that 130

whenever the workman removes the key plate mold line, that lap line register will result in the final multi-colored print, and whenever the key plate mold line is retained in 5 the negative that hairline, or butt register will result and so the character of the register can be mechanically adjusted to requirements of the finished multi-colored print. It will be apparent that by mechanically 10 moving only portions of the key plate mold I provide a negative in which both butt line and lap line register may be mechanically obtained.

After the negative has been prepared, it 15 is photographically printed upon sensitized metal in the customary manner, and if the workman has properly applied the opaque paint and made correct use of the key plate mold lines, either or both as positive or negative 20 lines, the result will be a print upon the metal containing the selected design contained in the negative base such as a half tone dot, and all guide lines and necessary drawing of the key plate, so that the work- 25 man may paint in solids upon the plate, and re-etch any part of the plate and portions of the design originally contained in the negative base (such as the half tone dot) and as 30 may be desired, all of which is done in the customary way. The final result is a plate which can be used as one of a set in the production of multi-colored prints, perfect in register with the other plate or plates of the set, the register being either lap-line or 35 butt-line as required, and varied in tone from solid to delicate high light.

After the photo print is made upon the sensitized metal, the negative base is washed with water, and gasoline or similar solvent 40 to remove the opaque paint and any portion of the key plate mold that was used in the negative and the negative base may then be reused.

Another method of using the negative 45 base is to make a print of the key plate upon paper, plate it beneath the negative base as a guide, and paint over portions of the negative base where the design is not to appear in the negative; the negative so prepared 50 is then photographically printed upon sensitized metal and etched, all in the customary manner, after which the negative base is washed off with water and then may be re-used.

55 I claim.

1. The method of producing a negative for use in producing a printing plate for one of a set of plates for multi-color printing which method comprises imposing an 60 opaque negative design upon a transparent sheet; then covering said design to embed the same in a composite negative base and protect such sheet from the action of gasoline and similar solvents and from the action of water; then building up upon said

negative base an embossed and friable key plate mold which may be removed by a stump and by the action of gasoline and similar solvents; and then applying to desired portions of such negative base a water 70 soluble opaque paint.

2. The method of producing a negative for use in obtaining a printing plate for one of a set of plates for multi-color printing which method comprises first imposing upon 75 a transparent sheet a negative design; then dusting said design while wet with a size powder of a different color than that of the design; then removing any surplus size powder; then thinly covering such dusted design with a transparent protective covering; then making a key plate impression upon the protective covering surface; then dusting the wet key plate impression with a dry powder to build up the same and make the key plate impression soft and friable; then rendering the friable impression water proof; then covering the surface of the sheet upon which the key plate impression is imposed with a coating of albumen; and then painting desired portions of the albumen surface with an opaque water soluble paint.

3. The method of producing a negative for use in obtaining a printing plate for one of a set of plates for multi-color printing which method comprises first imposing upon a transparent sheet a negative design; then dusting said design while wet with a size powder of a different color than that of the design; then removing any surplus size powder; then thinly covering such dusted design with a transparent protective covering; then making a key plate impression upon the protective covering surface; then dusting the wet key plate impression with a dry powder to build up the same and make the key plate impression soft and friable; then rendering the friable impression water proof; then covering the surface of the sheet upon which the key plate impression is imposed with a coating of albumen; then painting the desired portions of the albumen surface with an opaque water soluble paint; and then removing desired portions of the key plate impression.

4. The method of producing a negative for use in producing a printing plate for one of a set of plates for multi-color printing and introducing therein an embedded design, such as a half tone dot, said method comprising first printing upon a transparent non-absorbent sheet, that is insoluble in water or gasoline, an image of the picture to be produced in multi-colored prints; then treating portions of said sheet with an opaque water soluble solution which renders the surface bearing the printed negative image opaque but which does not penetrate said sheet or alter the print of the pic- 120
125
130

ture; then removing desired portions of said printed picture from said sheet and leaving a transparency graduated by the opaque negative design embedded in the sheet; then printing the resultant composite negative in the usual manner to obtain a printing plate; and then removing the opaque solution and remaining portions of the printed picture from said sheets so that the transparent sheet containing the embedded design 10 may be reused.

In testimony whereof, I have hereunto set my hand at Los Angeles, California, this 24th day of November, 1925.

BENJAMIN F. HUTCHISON.
